PRESSURE SEAL FOR WINDOWS AND DOORS

Helmut Lorenz, Dusseldorf, Germany

Application September 1, 1937, Serial No. 161,919½. In Germany September 7, 1936

3 Claims. (Cl. 20—68)

The invention relates to a device with which a packing of windows and doors, and in particular of outer doors, against draught, dust and rain water is effected. Simultaneously with this packing, the invention aims at effecting a sealing of the windows, and when desired also a pressing of the leaves or casements against the upper part of the frame.

The fundamental idea of the invention resides in providing on the window sill or on the threshold of the door a metal rail extending along the entire length thereof and, for example, substantially of U-form, over which a second metal rail extending parallel, but in the vertical direction, is displaceably arranged, the upper surfaces of which is adapted to the profile of the window or door frame to be packed. The movement of the movable packing rail and the pressing thereof against the window and door frames is, according to the invention, effected by a special drive, for example a suitable lever gear, independent of the door seal. Further particular features of the construction of such a pressure sealing device according to the invention will be seen from the accompanying drawing, in which:

Figure 1 is an elevational view of the window showing the new pressure seal in the opened position.

Figures 2 and 3 are sectional views of details of the pressure seal in the opened position.

Figure 4 is an elevational view and

Figures 5 and 6 are sectional views of the window, showing the pressure seal in the closed position, while

Figures 7 and 8 show a longitudinal section, and

Figure 9 a cross-section of a further constructional form.

In the drawing, the reference numeral 1 designates the pane and 2 the lateral frame of a window casement which is secured in the usual manner, for example by means of hinges 3, to the fixed wall frame 4.

The fastening of these parts of the window or of the window casement may be effected in any desired manner, for example with the aid of a sliding bar lock.

Between the window frame 2 and the lower sill 5 is situated a space. In this space is arranged a rail 6 of U-shaped profile, which rail lies on the sill 5 and is connected therewith by any desired means, for example by letting in. Over this rail there engages a second rail 7 also of U-shape, the upper surface 8 of which is, however, accurately adapted to the particular shape

of the under side of the window frame 2. For this purpose, the upper side 8 of the U-iron 7 may be bevelled to correspond to the inclination of the lower face of the window frame, and provided with a projection 9 engaging in a recess in the window frame. In the space enclosed by the U-irons 6 and 7 is arranged a rail, for example a flat iron 10, on both sides of which articulated levers 11, 12 pivotally secured at 13 engage. The articulated levers 12 are also pivotally arranged with their lower end on the ground sill 14 connected with the U-iron 6 or let in the said iron. The levers 11 pivotally engage with a fillet 15 rigidly connected to the U-iron 7. 15

Two further levers 16, 17 are pivoted with their outer ends to the lower fixed U-iron 6 and the upper movable U-iron 7, respectively. The inner ends of levers 16 and 17 are pivotally connected to one another, but the common pivot point of these levers is not connected to the flat iron 10. The assembly of levers 11, 12, 16 and 17 thus acts as a control system in such a manner, that the upper movable U-iron 7 can be raised and lowered without being inclined (see Fig. 4).

A rigid angle lever 19, 20 rotatably mounted at 21 pivotally engages at 18 with the end of the flat iron 10. A lever or handle 23 engages, also pivotally, with the free end of the arm 20 at 22. 30 The link pin 22 is preferably guided in a curved slot.

The lever 23 may also be actuated in any known manner, for example with the aid of a handle 25 lying at a higher level and adapted to 35 be readily gripped, and of a suitable transmission, for example a rack drive (see Figures 2 and 5).

Upon downward movement of the pin 22, the angle lever 19, 20 is turned in the direction of 40 the arrow. Consequently, the flat iron 10 is also displaced in the direction of the arrow into the position shown in Figures 4 to 6. The levers 11, 12 are thus straightened, so that the flat iron 10 and consequently also the U-iron 7 are lifted 45 and pressed against the under side of the window frame 2.

The movement of the connecting rod 10 is preferably so arranged that upon pressing of the rail 7 against the window frame 2 the levers 50 11, 12 are driven at least into the dead centre position, in which their axes form a straight vertical line, or better somewhat beyond this position. An automatic re-lowering of the rail with loosening of the seal is thus prevented. 55

By suitable selection of the transmission ratio and of the drive, very considerable pressing forces may be produced, so that not only a complete packing between the packing strip 7 and the 5 lower window frame 2 is effected, but the window leaf may also be raised somewhat according to requirement and pressed with its upper frame 26 against the upper brickwork frame 27 or against a corresponding packing strip.

10 The overlapping of the lower rail 6 by the U-iron 7 provides good protection of the connecting frame against rain, snow, dust, and the like, the raised parts 28 provided on the walls of the U-iron 6 acting as lubricating grooves affording 15 a good hold for any lubricating medium introduced, for example grease, and permitting sliding of the surfaces of the movable U-iron 7 with relatively little friction. Moreover, upon sliding on and off of the upper rail the paint of the 20 U-iron 6 is not damaged.

Owing to the lower absolutely tight seal effected with the aid of the U-iron, the lower weather rail normally provided on the outer side of all windows may be dispensed with.

25 Use may therefore now be made for fastening the window of a so-called "wolf's jaw", even if the window leaves open inwardly, while if weather rails be provided the "wolf's jaw" may be used only for outwardly opening windows. The 30 "wolf's jaw" fastener permits of a particularly good pressing of the window leaves in the lateral direction, so that the vertical joints of the outer window frame may be very well packed. In Figures 7, 8 and 9, such a "wolf's jaw" is shown in 35 combination with a new sealing device. In these figures, the reference numeral 29 designates a window leaf engaging with its protection 30 into the corresponding recess 31 of the leaf 32. In this constructional form, the fastening is effected by a rod 33 displaceably arranged in the 40 window leaf 32. The said rod has at its lower end a hook-shaped extension 34 which engages in a corresponding aperture 35 of the rail 7 when the leaf is closed. Upon pressing back of the 45 rail, the rod 33 is carried upwards and engages with its tapered extension 36 in a corresponding recess 37 in the upper brickwork frame 27 (see Figure 8).

With the new arrangement, almost complete 50 air tightness of these vertical joints may be obtained. As the same is also the case with the horizontal joints of the window owing to the lower pressure seal, it may be stated that with

the aid of the arrangement according to the invention the window may be sealed in an air-tight manner over its entire extent, so that it is very suitable for protection from the air and for all districts where such a tight sealing is desirable. 5

The invention may be modified in various respects within the scope of the essential idea. For example, the form of the U-rails and their packing surface may be varied and adapted to the 10 necessary fastening thereof to the sill, and to the special formation of the window frames. The mechanism for the movement of the U-rail, the number of driving members and the like may also be varied in various respects. For example, the 15 transmission may take place with the aid of a lower or toothed gear in the centre of the sill or, as shown in the illustrated example, on the side thereof. 20

What I claim is:

1. A weather-strip device for a casement window or its equivalent, said device being disposed on the sill of the window and comprising a first channelled member arranged horizontally on the sill with its limbs extending upwardly, a second channelled member arranged with its limbs extending downwardly and externally overlapping the upwardly extending limbs of said first member to form a passage therebetween, link mechanism within said passage operative to raise and lower said second channelled member whilst maintaining the limbs of the two members in overlapped relationship, and means external to the passage for actuating said link mechanism, whereby said second member when raised will 35 press against the under surface of said window when the latter is in closed position.

2. A weather strip device as set forth in claim 1, wherein said link mechanism comprises a pair of links pivotally connected together at one end 40 whilst the other end of each link is connected to one of said members to form a toggle joint, a push rod connected at one end to said pivotal connection and connected at its other end to said actuating means, and means for slidably supporting 45 said rod.

3. A weather strip device as set forth in claim 1, in which said actuating means comprises a lever mechanism operatively connected to said link mechanism and pivotally mounted at the 50 side of the window frame.

HELMUTH LORENZ.
